UNITED STATES PATENT OFFICE

116,955

DESIGN FOR A FROZEN FOOD CABINET

Robert Winter Hull, Connersville, Ind.

Application August 17, 1938, Serial No. 79,407

Term of patent 3½ years

To all whom it may concern:

Be it known that I, Robert Winter Hull, a citizen of the United States, residing at Connersville, in the county of Fayette and State of Indiana, have invented a new, original, and ornamental Design for a Frozen Food Cabinet, of which the following is a specification, reference being had to the accompanying drawing, forming part thereof.

Fig. 1 is a perspective view of a frozen food cabinet showing my new design.

Fig. 2 is a perspective view on a reduced scale of the same cabinet, but illustrating the two opposite vertical sides thereof.

I claim:

The ornamental design for a frozen food cabinet, as shown.

ROBERT WINTER HULL.
